DESIGN FOR A SHOE

Theodore Samuels, St. Louis, Mo.

Application May 26, 1936, Serial No. 62,847

Term of patent 3½ years

To all whom it may concern:

Be it known that I, Theodore Samuels, a citizen of the United States of America, residing in St. Louis and State of Missouri, have invented a new, original, and ornamental Design for a Shoe, of which the following is a specification, reference being had to the accompanying drawing, forming part thereof.

I claim:

The ornamental design for a shoe substantially as shown.

THEODORE SAMUELS.
